(57) **CLAIM**

The ornamental design for a guitar pick sling, as shown and described.

DESCRIPTION

FIG. 1 is a perspective view of the guitar pick sling, which embodies my design;

FIG. 2 is a perspective view of the guitar pick sling, showing the strap portion in an alternate position;

FIG. 3 is a side view of the guitar pick sling of FIG. 2;

FIG. 4 is an opposite side of the guitar pick sling of FIG. 3;

FIG. 5 is a side view of the guitar pick sling of FIG. 1;

FIG. 6 is an opposite side view of the guitar pick sling of FIG. 5;

FIG. 7 is a top plan view of FIG. 1;

FIG. 8 is a bottom plan view of FIG. 1;

FIG. 9 is an exploded perspective view of FIG. 1; and,

FIG. 10 is a perspective view of FIG. 2, the broken line showing of the human hand is for illustrative purposes only and forms no part of the claimed design.
